PROCESS FOR ISOLATING LEVULOSE AS THE LIME LEVULATE

Ralph Malcolm Hixon, James Harvey McGlumphy, Jack Waldo Eichinger, Jr., and John Hall Buchanan, Ames, Iowa, assignors to Iowa State College of Agriculture and Mechanic Arts, Ames, Iowa, a corporation of Iowa

Application July 30, 1931, Serial No. 554,082

8 Claims. (Cl. 127—36)

The principal object of this invention is to provide a process for isolating levulose as the lime levulate which will yield a precipitate that is readily and easily filtered.

5 A further object of our invention is to provide a process for isolating levulose as the lime levulate which may be used at normal temperatures and which does not require a certain fixed low temperature as has heretofore been 10 the case.

A still further object of this invention is to provide a process for the isolating of levulose as the lime levulate in which the precipitation of the lime levulate is rapid and convenient.

15 A still further object of our invention is to provide a process for isolating levulose as the lime levulate which leaves the precipitated lime levulate in a granular form, which may be washed sufficiently free from impurities so that 20 the regenerated levulose will crystallize immediately from the resulting syrup when seeded.

These and other objects will be apparent to those skilled in the art.

Our invention consists in the method herein- 25 after set forth, pointed out in our claims and illustrated in the accompanying drawings, in which:

Fig. 1 is a diagrammatical cross sectional view of a satisfactory arrangement of apparatus 30 which may be utilized for the formation of lime levulate.

Fig. 2 is a side sectional view of the method of raising or lowering an over-flow pipe.

Fig. 3 is a cross sectional view, taken on line 35 3—3 of Fig. 1.

Fig. 4 is a cross sectional view of a portion of the lime suspension kettle showing another method of raising or lowering the over-flow pipe.

Fig. 5 is a cross sectional view taken on line 40 5—5 of Fig. 4.

This invention relates to a process for isolating levulose as the lime levulate. The isolation of levulose as the lime levulate has generally been considered the most practical method of preparing levulose. Due to the fact that heretofore it has been difficult to precipitate the lime levulate because of the low temperature in which this processing must be done, this method has never been commercialized. Heretofore it has 45 been necessary to precipitate the lime levulate at a temperature of between minus five degrees centigrade to plus five degrees centigrade and then to filter the gelatinous precipitate so obtained. It has been found almost impossible to 50 wash this gelatinous precipitate sufficiently free from impurities that crystallization of the regenerated levulose can be accomplished directly from water.

We have discovered after extensive experiments 55 that if a levulose solution and a lime suspension

are allowed to flow slowly in the correct proportions into a sufficiently large volume of seed and stirred efficiently, that a granular and easily filterable precipitate of lime levulate results.

The numeral 10 designates a kettle for containing a levulose solution having therein a float 11, which rests on top of the levulose solution and to which is attached a rope or the like 12. The rope 12 passes over a pulley wheel 13 which is rotatably mounted on a suitable rack or the like. 65 The numeral 14 designates a large pulley wheel 70 pivotally mounted on a suitable rack. At the end of the rope 12, after it has passed over the pulley wheel 14 is a weight 15.

The numeral 16 designates a lime suspension 75 kettle having rotatably mounted at its center a shaft 17 to which is secured the stirring blades 18 and which may be rotated by a suitable means. The numeral 19 designates a rack secured to the side of the lime suspension kettle having a slot 20. 80 The numeral 21 designates a flexible hose which is slidably mounted in the slot 20 by the ferrule 22. Secured to this ferrule 22 is a rope or the like 23 which passes over a pulley wheel 24 and thence secured to a pulley wheel 25, which is secured to 85 the large pulley wheel 14, as shown in the drawings. The numeral 26 designates a pipe having one end in communication with the flexible hose 21 and having its other end in communication with the lower side of the lower end portion of a 90 precipitating kettle 27. The precipitating kettle 27 has pivotally mounted in its center a shaft 28, having secured to its lower end portion a propeller blade 29 to facilitate the stirring of the suspension. The shaft 28 may be rotated by any suitable 95 means.

The numeral 30 designates a pipe or the like 100 communicating with the inside of the levulose solution kettle 10 and with the precipitating kettle 27 and having interposed therein a valve 31 for controlling the amount of levulose solution entering the precipitating kettle. Near the top of the precipitating kettle 27 is a pipe 32, which allows the solution, after it has reacted, to flow into a storage tank 33. In the modified form of construction shown in Fig. 4 and Fig. 5 for lowering and raising the hose 21 we have used the numeral 105 34 to designate a guide secured to the side of the lime suspension kettle to allow an over-flow cup 35 to travel up and down as required, by having integrally formed on this over-flow cup a T-shaped member 36, which rides in the slot formed by the guide 34. The numeral 37 designates a cross member in the over-flow cup 35 to which is secured the rope 23. The cup 35 is actuated by 110 the same means as is the ferrule 22. The reaction kettle 27 and the storage kettle 33 may be jacketed if temperature control is desired.

It will be seen from the foregoing that the height of the levulose solution in the kettle 10 will 115 120

control the amount of over-flow from the lime suspension kettle 16, through the flexible hose 21, the pipe 26 and into the precipitating kettle 27. As the float 11 is lowered, due to the drawing out of the levulose solution, it will, through the medium of the rope 12, rotate the pulley wheels 13 and 14. As the pulley wheel 14 revolves it will cause the rope 23, secured to the pulley wheel 25 to be let out, thereby lowering the end of the over-flow hose.

10 The amount of levulose solution entering the precipitating kettle 27 is controlled by the valve 31.

15 Both the sugar solution and the lime suspension enter the precipitating kettle 27 when they react to form the lime levulose in the presence of a predominating quantity of seed, which offers a large area for crystal growth with resulting granular nature of the precipitate and its ease of filtration.

20 As the reactants are added, the suspension of lime levulose over-flows from the precipitating kettle 27, through the over-flow pipe 32, to a storage tank 33 or to a continuous filter.

25 As an example of this process, clarified and hydrolyzed Jerusalem artichoke extract containing ten percent solids and a suspension of hydrated lime in the ratio of one liter of extract to two hundred cubic centimeters of lime were allowed to flow slowly into a vessel or precipitating kettle

30 in which they were kept stirred. The reactants were introduced into the bottom of the container and the lime levulose suspension allowed to overflow at the top of the container. After the procedure had become continuous filter cakes of one-half inch thickness were deposited upon filters in one and one-half minutes. This precipitate is of such a granular nature that it can be easily handled and washed on the various types of continuous filters.

35 40 Another method for the formation of lime levulose is to allow a quantity of levulose solution to flow slowly into the required amount of lime suspension to give a slight excess over that sufficient for precipitating the lime levulose. This method is a suitable process for preparing a volume of lime levulose to serve as seed in starting the first mentioned continuous method.

45 50 When the lime levulose prepared by either of the above methods was converted to free levulose, syrups of such a high degree of purity were obtained that spontaneous crystallization would take place from syrups of eighty-six percent solids within twenty-four hours. When such syrups were seeded at fifty degrees centigrade and the temperature dropped slowly to twenty-five degrees centigrade at the rate of one degree per hour, granular levulose resulted, about two pounds of white crystalline levulose were obtained from six pounds of syrup. These examples are illustrative of the principle, many variations being possible.

55 60 We claim as our invention:

65 70 1. A process for isolating levulose in the form of a lime-levulose suspension comprising the following steps: introducing a lime suspension and a levulose-containing solution into a vessel and in the presence of a large volume of seed, agitating the combined matter in the vessel, and allowing the resultant lime-levulose suspension to pass from the vessel.

75 80 2. A process for isolating levulose in the form of a lime-levulose suspension which comprises the

85 following steps: introducing an agitated lime suspension into a vessel, introducing a levulose-containing solution into the said vessel and in the presence of a large volume of seed, agitating the combined matter in the vessel, and allowing the resultant lime-levulose suspension to pass from the vessel.

90 95 3. A process for isolating levulose in the form of a lime-levulose suspension which comprises introducing an agitated lime suspension into a vessel, introducing a levulose-containing solution into the said vessel, and in the presence of a large volume of seed, agitating the combined matter in the vessel, and allowing the resultant lime-levulose suspension to pass from the vessel at a temperature substantially above five degrees centigrade.

100 105 4. A process for isolating levulose in the form of a lime-levulose suspension comprising the following steps: introducing a lime suspension and a levulose-containing solution into a vessel and in the presence of a large volume of seed, agitating the combined matter in the vessel, and allowing the resultant lime-levulose suspension to pass from the vessel, the lime suspension and the solution being introduced into the vessel near the bottom thereof, and the resultant suspension being passed out of the vessel remote from the bottom thereof.

110 115 5. A process for isolating levulose in the form of a lime-levulose suspension which comprises the following steps: introducing an agitated lime suspension into a vessel, introducing a levulose-containing solution into the said vessel and in the presence of a large volume of seed, agitating the combined matter in the vessel, and allowing the resultant lime-levulose suspension to pass from the vessel, the lime suspension and the solution being introduced into the vessel near the bottom thereof, and the resultant suspension being passed out of the vessel remote from the bottom thereof.

120 125 6. A process for isolating levulose in the form of a lime-levulose suspension which comprises introducing an agitated lime suspension into a vessel, introducing a levulose-containing solution into the said vessel, and in the presence of a large volume of seed, agitating the combined matter in the vessel, and allowing the resultant lime-levulose suspension to pass from the vessel at a temperature substantially above five degrees centigrade, the lime suspension and the solution being introduced into the vessel near the bottom thereof, and the resultant suspension being passed out of the vessel remote from the bottom thereof.

130 135 7. A process for isolating levulose in the form of a lime-levulose suspension which includes the step of separately introducing a lime suspension and a levulose-containing solution to a single large batch of seed.

140 145 8. A process for isolating levulose in the form of a lime-levulose suspension which includes the step of separately introducing a lime suspension and a levulose-containing solution to a single large batch of seed, at a temperature substantially above 5° centigrade.
